UNITED STATES PATENT OFFICE.

HUGO SOHMER, OF NEW YORK, N. Y.

DESIGN FOR A PIANO-CASE.

SPECIFICATION forming part of Design No. 15,250, dated August 12, 1884.

Application filed June 5, 1884. Term of patent 7 years.

To all whom it may concern:

Be it known that I, HUGO SOHMER, of the city, county, and State of New York, have invented a new and original Design for Cases for Grand Pianos, of which the following is a full, clear, and exact description, reference being had to the accompanying drawings, making part of this specification, in which drawings—

10 Figure 1 represents a plan, and Fig. 2 a side elevation, of my case for grand pianos.

The design relates to a case for grand pianos; and it consists of a case having a rectangular front portion, curved side portions or 15 offsets, and a semicircular rear portion.

10 *a* represents the rectangular front portion, and *b* the semicircular rear portion, of my case for grand pianos. The rear portion, *b*, is of less width than the front portion, and connected with the latter by curved side portions

or offsets *dd* and straight side portions *ee*. A more symmetrical shape and a better appearance is thereby imparted to the case for grand pianos than when one side is straight and the other curved, as has been the case 25 heretofore.

Having thus described my design, I claim as new and desire to secure by Letters Patent—

The design for a case for grand pianos, consisting of a rectangular front portion, *a*, straight side portions, *ee*, curved offsets *dd*, and a semicircular rear portion, *b*, as shown and described.

In testimony that I claim the foregoing as my invention I have signed it this 27th day of 35 May, 1884.

HUGO SOHMER.
